ORTHOPEDIC SHOE

Nunzio D. Calvilli, Bronx, N. Y.

Application November 19, 1941, Serial No. 419,677

2 Claims. (Cl. 36—71)

This invention relates to shoes, and has particular reference to orthopedic shoes.

One object of the invention is to provide a shoe of the character described having improved means to correct foot deformities or conditions causing callouses, or to alleviate the sufferings resulting therefrom.

Another object of the invention is the provision of a shoe of the nature set forth having improved means particularly adapted for the orthopedic treatment of the metatarsal region of the foot.

Another object of the invention is to furnish a shoe of the type referred to having improved means to provide a sole having inherent resilience or yielding qualities operative especially in conjunction with the orthopedic arch which tends to flatten downward the forward part of the foot.

Other objects and advantages of the invention will become apparent as the specification proceeds.

With the aforesaid objects in view, the invention consists in the novel combinations and arrangements of parts hereinafter described in their preferred embodiments, pointed out in the subjoined claims, and illustrated in the annexed drawing, wherein like parts are designated by the same reference characters throughout the several views.

In the drawing:

Figure 1 is a sectional view of a shoe embodying the invention, with parts removed.

Fig. 2 is a bottom view of the sole.

Fig. 3 is a sectional view taken on line 3—3 of Fig. 1.

Fig. 4 is a fragmentary sectional view of a modification of the invention.

Fig. 5 is a section taken on the line 5—5 of Fig. 4.

The advantages of the invention as here outlined are best realized when all of its features and instrumentalities are combined in one and the same structure, but, useful devices may be produced embodying less than the whole.

It will be obvious to those skilled in the art to which the invention appertains, that the same may be incorporated in several different constructions. The accompanying drawing, therefore, is submitted merely as showing the preferred exemplification of the invention.

Referring in detail to the drawing, 10 denotes a shoe embodying the invention. The same may comprise a sole 11 having a plurality of layers of material, such as the main sole section 12 that preferably consists of leather. There is also any heel 13 that may consist of rubber, leather, or other desirable material. At a suitable area along its length the sole may comprise any proper orthopedic arch 14. In advance of this arch and beginning at a point adjacent thereto is a

recess or opening 15 of sufficient size to underlie a substantial portion of the metatarsus of the foot. This opening 15 is spaced from the side edges of the sole, and is desirably elongated toward the toe portion of the shoe. Preferably the opening 15 is of maximum depth adjacent to the arch 14 and diminishes gradually in depth toward the toe portion of the shoe. Thereby the sole of the shoe becomes a permanently elastic bridge, whose span is determined by the width of said opening.

The conjoint orthopedic action of the arch 14 and the opening 15 is that the former, among its other well known functions, tends to shift part of the weight on the foot forwardly, thereby causing the forward part of the foot to flatten down. Corresponding to this action, the sole is relatively plane, to afford the ideal condition of the foot in walking. As a result of this corrective downward flattening of the forward part of the foot, the pressure at the front end portion of the metatarsal arch is substantially increased and this leads to various difficulties which have heretofore perplexed the art. Thus various cushioning devices have been provided to ease the pressure, but these have proven ineffective. For example, sponge rubber, which has been greatly favored, has been found to be inadequate because it loses its resilience and tends to become lifeless. Metallic springs have been of some help, but they require exceedingly expert fitting and present various drawbacks which may not be apparent until a person has worn the shoe for some time. They greatly increase the cost of manufacture, and have various limitations in respect to positioning and anchorage thereof in the sole of the shoe. These difficulties are solved by the slotted or recessed sole, which thus affords an inherent, non-displaceable cushion for the foot.

I may provide a supplemental cushioning member 16 of a highly resilient or porous yielding material such as sponge rubber, but the advantages thereof are best realized in conjunction with the conjoint action of the arch 14 and the opening 15 which are adjacent thereto, and as will now be briefly described, it being understood that the arch 14 is of sufficient height to support the head of the metatarsal arch.

As the foot is shifted or urged forwardly by the arch 14, and in consequence flattens down, the pressure on the sponge rubber member 16 is substantially increased. But this added pressure is instantly counteracted by the softness of the member 16, and as it becomes compressed, the pressure is increasingly imparted to the central area of the sole 11, which yields downwardly at the opening 15. This produces a transverse flexure of the sole, which may be a maximum near the arch 14 and which diminishes toward the toe

portion of the shoe. Thus the sponge rubber member 16 and the recessed sole portion together form a spring which initially deforms easily, but which gradually becomes much stiffer to resiliently carry a substantial weight. Since the 5 sponge rubber member overlies and extends beyond certain adjacent edges of the opening 15, there is a gradual pressure transition over the edges of the opening so as to avoid any possible discomfort. With a leather of good quality, the 10 resilience of the sole will be indefinitely maintained, and the elastic action of the shoe will not be impaired in any material degree even if the sponge rubber eventually loses much of its springiness. Thus the relatively sharp increase of pressure closely to the forward end of the arch 14 is taken care of in a manner that is readily adapted to the feet of many different persons. This is an 15 important characteristic especially in a shoe such as herein disclosed, which is adapted for quantity production.

Desirably the opening 15 is formed by making a cut out in a sheet of leather 17 which is beveled off rearward and tapered off forward as shown. This sheet member 17 may be pasted to the sole 20 member 12, and the outside edges beveled off so that it becomes quite inconspicuous.

Overlying the front section of the sole member 12 is a sheet of a soft yielding material such as cork that may be formed with an opening to receive the sponge rubber member 16. Extending over the latter and the member 18 is another sheet 19 of soft yielding material such as cork, which may form the insole and may be reenforced by a top layer 20 of any suitable pliable fabric such as a sheet of very thin leather or textile fabric. This insole 19, 20 may also extend over the arch 14, whose core may consist of a body 21 of cork or other suitable material; and said insole may also extend over the heel 13, preferably 40 with the provision of an intermediate cork layer 22. In order not to expose the cork layers 18, 19 and 22 at the edges of the sole, marginal strips 23 of leather may be disposed to enclose the cork material.

If desired, a sponge rubber insert 24 may be provided at the heel, as by forming a recess therein and an opening 25 in the adjacent part of the layer 12. Similar inserts may be provided at other points in the shoe, for example, under the big toe of the foot or wherever special pressure areas exist.

In Figs. 4 and 5 is shown a shoe 26 having a sole 27 according to a modification of the invention, which illustrates how an opening such as 15 may be disposed within the body of the sole. Here the main sole layer is 12a, with the elongated central opening 15a being formed in the layer 17a so that the said opening lies in the same relationship to the arch 14a as illustrated for the shoe 10. Overlying the deepest part of the opening 15a is the sponge rubber member 16a, but preferably I provide an intermediate leather sheet 28 having an opening 29. Thus the member 16a may normally lie above the layer 28 as in Fig. 4, but under pressure it may bulge down into the opening 29 as in Fig. 5, and may even bear down on the layer 12a. If desired, the opening 29 may be omitted, but the structure shown is desirable for severe foot ailments. The 70 sole is completed by the cork layers 18a and 19a and by the finishing top layer 20a.

The operation and advantages of the shoe may be substantially like those of the shoe 10, except that the sponge rubber member is deflectable in part into an opening or recess for increased resilience.

Although the soles are shown as consisting of various layers, it will be understood that these may be reduced or varied. Thus the openings such as 15 and 15a may be formed by molding or in other suitable manner. The term "layer" may thus denote section. Although leather is particularly referred to herein, it will be understood that other materials, composition or natural, may be used which have the requisite elasticity, strength, and durability. The term "leather-like" may denote all such materials. Preferably the materials used should permit free evaporation of perspiration and for this reason I prefer to employ adhesives suitable for that purpose in securing together the various layers herein shown.

It will thus be seen that I have provided an orthopedic shoe which fulfills the objects of the invention and is well adapted for practical use.

I claim:

1. A shoe having a sole consisting principally of leather and having the characteristic resilience thereof, the sole having an elongated external recess spaced from the side edges thereof and having its inner end at the front end of the metatarsal arch of the foot and extending continuously to the front end of the sole, the sole being of such uniform thickness at all points of the recess as to maintain transverse resilience in the sole along the recess, said recess increasing in depth toward its inner end to afford a maximum range of flexibility with respect to the bottom surface of the sole, the portion of the sole beyond the said inner end having the full thickness of the sole and being closely adjacent to the metatarsal arch and constituting the only abutment transverse to said recess, and the bottom face of the sole lying otherwise in a plane, the sole comprising a member of porous cushioning 45 material located above the recess solely adjacent to and forward of the transverse abutment.

2. A shoe having a sole consisting principally of leather and having the characteristic resilience thereof, the sole having an elongated external recess spaced from the side edges thereof and having its inner end at the front end of the metatarsal arch of the foot and extending continuously to the front end of the sole, the sole being of such uniform thickness at all points of the recess as to maintain transverse resilience in the sole along the recess, said recess increasing in depth toward its inner end to afford a maximum range of flexibility with respect to the bottom surface of the sole, the portion of the sole beyond the said inner end having the full thickness of the sole and being closely adjacent to the metatarsal arch and constituting the only abutment transverse to said recess, and the bottom face of the sole lying otherwise in a plane, the sole comprising a metatarsal arch spaced rearward of the recess, and a member of porous, resilient cushioning material located in advance of the arch and overlying the recess only at its area of maximum depth.

NUNZIO D. CALCULLI.
